UNITED STATES PATENT OFFICE.

ELEAZER KEMPSHALL, OF NEW YORK, N. Y.

PEN.

1,012,862.

Specification of Letters Patent. Patented Dec. 26, 1911.

Application filed April 6, 1911. Serial No. 619,416.

To all whom it may concern:

Be it known that I, ELEAZER KEMPSHALL, a citizen of the United States, residing at New York city, in the county of New York and State of New York, have invented certain new and useful Improvements in Pens; and I do hereby declare the following to be a full, clear, and exact description of the invention, such as will enable others skilled 10 in the art to which it appertains to make and use the same, reference being had to the accompanying drawings, and to letters or figures of reference marked thereon, which form part of this specification.

15 This invention relates to improvements in pens.

The object of the invention is to provide means for forming wells to retain ink, when the pen is dipped preparatory to writing.

20 A further object of the invention is to provide the pen with a well on opposite sides to increase the efficiency of the pen and to prolong the writing period without frequent dipping of the pen in an ink well.

25 The invention also relates to improvements in the details of construction and arrangement of parts, which will be herein-after described, and particularly pointed out in the claims.

30 In the drawings:—Figure 1 is a plan view of my improved pen. Fig. 2 is a bottom plan view of the same. Fig. 3 is a longitudinal section. Fig. 4 is a cross section of the pen.

35 1 indicates a pen provided with the usual body portion which is pointed at 2, and formed with a slit 3. In the body portion, and intersecting the slit is a depression or continuous well 4, stamped in the metal, and 40 adapted to hold ink when the pen is dipped, preparatory to writing. The walls of the well 4, project slightly below the bottom surface of the body of the pen to afford sufficient depth to retain the ink, so that 45 the latter will flow freely through the slit.

In the center of the well 4, is a hollow spherical enlargement which projects upwardly, to form a lower ink well 5, the slit 3 extending through both wells 4 and 5.

50 At the front of the base of the hollow spherical enlargement is a short transverse slit 6, which intersects the slit 3, whereby to assist the ink in flowing from both wells 4 and 5 to the slit 3.

55 In use the pen is dipped in ink in the

usual manner, and the ink will flow into the wells 4 and 5, as well as on the upper and lower surfaces of the end of the pen. When writing the ink on the surfaces of the pen will of course run to the point first in the 60 same manner as an ordinary pen. Then after this ink is used, that contained in the wells will flow through the slit to the point which permits a great number of words to be written without the inconvenience of frequent dipping, or the necessity of additional expense covering the cost of a fountain pen. 65

The invention is extremely simple, and as the wells are formed by stamping the metal, no additional cost is involved in manufac- 70 turing or assembling parts.

What I claim is:

1. A pen provided with a raised portion and a depression surrounding the same said depression forming a well, the pen having 75 a slit extending from the point of the pen and intersecting the well.

2. A pen provided with a raised portion and a depression surrounding said raised portion to form the base of the raised portion having a transverse slit, the pen being formed with a slit extending from the point of the pen and intersecting the depression and the transverse slit. 80

3. A pen provided with a well located 85 above the surface of the pen, and a well located below the surface of the pen, said pen having a slit which intersects both wells.

4. A pen provided with a depression forming a well, a hollow projection within 90 the depression to form a second well, said pen having a slit which intersects both wells.

5. A pen provided with a depression forming a well and formed with a slit extending from the point of the pen and intersecting the depression, one wall of the depression having a transverse slit which intersects the before mentioned slit, the center of the well having a bulged portion 95 which is also intersected by the slit. 100

6. A pen formed with a depression in its upper surface to provide an upper well, a hollow spherical projection in the center of the depression to form a well in the bottom of the pen, said pen having a slit extending 105 from the point and intersecting the two wells.

7. A pen formed with a depression in its upper surface to provide an upper well, a hollow spherical projection in the center of 110

the depression to form a well in the bottom of the pen, said pen having a slit extending from the point and intersecting the two wells, the one well of the depression having a transverse slit which intersects the before mentioned slit.

8. A pen provided with a depression in its upper surface to form a well around a central portion of the metal of the pen, the 10 said pen having a slit extending from the

point of the pen and intersecting the front and rear portions of the depression.

In testimony whereof I have signed my name to this specification in the presence of two subscribing witnesses.

ELEAZER KEMPshall.
